UNITED STATES PATENT OFFICE.

ALBERT L. BUTLER AND MILAN C. BULLOCK, OF CHICAGO, ILLINOIS.

STRIKING-DRILL FOR MINING PURPOSES.

SPECIFICATION forming part of Letters Patent No. 236,774, dated January 18, 1881.

Application filed October 29, 1880. (No model.)

To all whom it may concern:

Be it known that we, ALBERT L. BUTLER and MILAN C. BULLOCK, of the city of Chicago, in the county of Cook and State of Illinois, have invented certain new and useful Improvements in Striking-Drills for Mining Purposes; and we do hereby declare that the following is a full, clear, and exact description of the invention, which will enable others skilled in the art to which it appertains to make and use the same, reference being had to the accompanying drawings, and to the letters of reference marked thereon, which form a part of this specification.

Our object is the production of an effective striking-drill, first, which will be of such spiral form as to effectually free the hole being drilled from chips; second, in which the necessity of frequently shaping and forging the cutting end after the points or blades shall have worn away is avoided by making its contour the same throughout its length; third, that by such uniform contour any part or section of the drill, if broken at any point in its length, may be effectively used without forging the same; fourth, that the body and shank of the drill may be of the same size and strength as the cutting end; fifth, making the holding-socket of the piston of such form or contour as that the head and likewise any section of the drill may be firmly held by such holding-socket, so that if the drill be cut or broken off at any point in its length the long piece, or any portion left, may be immediately inserted into the socket and the work proceed without waiting to forge another head upon said piece to fit the said socket.

The invention consists, first, in a striking-drill grooved or flanged spirally throughout its entire length, and having the cutting-edge of the same diameter as that of the drill at any point.

The invention consists, secondly, in combining with such a drill a holding-socket of such interior form or contour as will adapt it to receive the head or any section of the drill, so that if the drill should be cut or broken off at any point in its length any part of the drill may be inserted within the socket.

The invention consists, thirdly, in combining in a percussion drilling-machine a spirally

grooved or flanged drill with a piston-rod carrying a socket whose interior form or contour adapts it to receive and hold the head or any part of the length of said drill.

Such a drill may be made either by rolling the metal to the desired form of cross-section and then twisting the same, or in any other suitable manner, producing a spirally-grooved drill, or (and preferably) one of equal diameter and form throughout.

The drawings illustrate only one of the many forms of spiral for such drills which may be used.

Figure 1 represents a perspective view of a drilling-machine with our improvements attached. Fig. 2 is a side view of our twisted drill. Fig. 3 is an end view of the same. Fig. 4 is a side view of the head with a part of the socket removed. Fig. 5 is a view of the same with the cap on.

A represents the twisted drill; B, the drilling-machine; C, the end of the piston-rod; D, the ordinary encircling strap; F, the cap, which is clamped firmly to the drill by means of the nut E.

It will be seen that the socket at the end of the piston-rod has such interior formation as will allow it to receive any portion of the length of the drill, the socket having spiral recesses or grooves corresponding in shape and pitch with the spiral flanges of the drill.

In addition to the advantages possessed by our invention, as above pointed out, it may be stated that by giving to the spirally grooved or flanged drill a diameter common to all parts of its length and cutting-point the hole which is being drilled is kept freer from chips than by the use of drills with an enlarged striking end. This may result from the increased diameter of the drill as an elevating medium in carrying up the chips, which, in one revolution, will lift a greater quantity than a drill of smaller diameter, or from there being less annular space left between the drill and the sides of the hole for the accumulation of chips. It is also found that friction is reduced in the use of this drill.

A noticeable advantage attending the use of a socket interiorly grooved to receive the spiral flanges of the drill is, that the concusion, which in other forms of socket is concen-

trated upon a small resisting-surface, is in this case distributed throughout the socket with the best possible results, as every portion of the drill within the socket imparts the concusion to a similarly-shaped bearing-surface in the socket.

A socket of this description is specially and conveniently adapted for use as a part of a piston in a percussion drilling-machine, in which relation it is here shown and claimed.

We are aware that spiral drills for metal-working and also for rock-drilling are not new; but, with respect to rock-drills, we are unaware that any have heretofore been used of a common diameter throughout their entire length and at their cutting-points.

The use of such twisted or spirally flanged or grooved rock-drills as have heretofore been used is not, we believe, attended with the advantages which are connected with the use of drills of our construction.

What we claim, and desire to secure by Letters Patent, is—

1. A spirally grooved or flanged drill having

a diameter common to all parts of the length 25 of its body and cutting-points, substantially as described.

2. A spirally grooved or flanged drill having a common shape and diameter throughout its entire length, combined with a holding-socket 30 the interior form or contour of which adapts it to receive and hold the head or any part of the length of said drill, substantially as described.

3. In a percussion drilling-machine, a spirally grooved or flanged drill, combined with 35 a piston-rod carrying a socket the interior form or contour of which adapts it to receive and hold the head or any part of the length of said drill, substantially as specified.

In witness whereof we hereunto affix our signatures, in the presence of two witnesses, this 19th day of October, A. D. 1880.

ALBERT L. BUTLER.
MILAN C. BULLOCK.
